ATTYS.

UNITED STATES PATENT OFFICE.

EDDY T. THOMAS, OF NEW YORK, N. Y., ASSIGNOR TO THE GOLD MEDAL SEWING MACHINE COMPANY, OF ORANGE, MASSACHUSETTS.

SEWING-MACHINE ATTACHMENT.

SPECIFICATION forming part of Letters Patent No. 244,093, dated July 12, 1881.

Application filed February 16, 1881. (Model.)

To all whom it may concern:

Be it known that I, EDDY T. THOMAS, of city, county, and State of New York, have invented a new and useful Improvement in Sewing-Machine Attachments, of which the following description, in connection with the accompanying drawing, is a specification.

This invention in sewing-machine attachments has for its object the combination, in a single attachment, of two or more binders and a hemmer, the binders and hemmer being all attached to the same holding-plate, the latter being provided with a hole for each binder and hemmer, the said holes being located at different distances from the center of the holding-plate, so that the front edges of the binders and hemmer, although of different widths, will always fall in proper position with relation to the machine-needle when the set-screw to hold the attachment to the cloth-plate is inserted in the hole made in the cloth-plate to receive it, and also in the hole of the holder next the hemmer or binder to be used.

The drawing represents, in top view, an attachment comprising a set of binders and a hemmer secured to one holding-plate provided with holes in accordance with my invention.

The circular holding-plate A has connected with its periphery, as herein shown, a set of three binders, *a b c*, of different sizes and styles, but not of any shape or style peculiarly of my invention. The hemmer *d* is also secured to the said holder.

Opposite each binder and the hemmer the holder is provided with holes *e f g h*, some of which are at different distances from the center of the holder A, so that when the usual attachment or gage-screw of the sewing-machine

has been placed in one of the said holes nearest the binder or hemmer to be used, and screwed into the hole made in the cloth-supporting bed or plate of the sewing-machine, the outer edges of the said binder or hemmer will be placed exactly in proper line with relation to and at just the proper distance from the needle of the sewing-machine for the latter to just catch the edges of the binding or the hem turned by the hemmer, thus avoiding the necessity of adjusting the same longitudinally under the screw and on the said bed, as heretofore necessary when the holding-plate is slotted in the usual manner.

I claim—

1. A sewing-machine attachment consisting of a circular metal plate provided with holes, one for each binder and hemmer, combined with the set of three binders *a b c* and a hemmer, *d*, all rigidly secured to the said holder, substantially as described.

2. As an improved article of manufacture, a sewing-machine attachment composed of a holder, a set of two or more binders of different sizes, and a hemmer, all permanently connected thereto, the holes in the holder adapted to receive the usual gage or holding screw being made therein at different distances from the center of the holder, according to the width of the binder or hemmer, all substantially as and for the purpose described.

In testimony whereof I have signed my name to this specification in the presence of two subscribing witnesses.

EDDY T. THOMAS.
